Primary Examiner — Marianne Pandozzi*Assistant Examiner* — Jae Liang(74) *Attorney, Agent, or Firm* — Gulf Coast Intellectual Property Group(57) **CLAIM**

The ornamental design for a vest with integrated fluid chambers and straw, as shown and described.

DESCRIPTION

FIG. 1 is a in use perspective view of a vest with integrated fluid chambers and straw showing my new design;

FIG. 2 is a front view thereof;

FIG. 3 is a rear view thereof;

FIG. 4 is a right side view thereof; and,

FIG. 5 is a left side view thereof.

The broken line showing in the figure drawings are included for the purpose of illustration and form no part of the claimed design.
